CASH REGISTER AND ACCOUNTING
MACHINE

Karl Bullerjahn, Berlin-Neukolln, Germany, assignor to The National Cash Register Company, Dayton, Ohio, a corporation of Maryland

Application September 5, 1935, Serial No. 39,210
In Germany November 17, 1934

7 Claims. (Cl. 235—2)

The invention relates to cash registers and accounting machines provided with a printing device having several printing places at which during a machine operation two different record materials, as for instance, a pass-book and a ledger card, can successively be imprinted. Such a machine is shown and described in the United States Letters Patent No. 1,628,336 to B. M. Shipley to which reference may be had for a detailed description.

It often happens that, for some reason, the pass-book is not available when the original entries are made and, under these circumstances, a record is made on a receipt instead of in the pass-book. As a result of this, supplementary entries must often be made in the pass-books, and, in these supplementary entering operations, the second printing operation must be eliminated in order that a record, which could ordinarily be made by such an operation, may not be made and used for an improper purpose.

Thus, the main object of the invention is to adapt a printing hammer actuating mechanism which normally effects several successive impressions in a machine operation so that it will perform a single stroke in each subsequent supplementary entering operation.

Another object of the invention is to provide printing hammer control means adapted to be actuated after the first hammer stroke by a special key depressed in an adding operation and by the total lever displaced in a subsequent total taking or balancing operation.

Further object of the invention will be pointed out in the following detailed description with reference to the annexed drawings.

A preferred form of an embodiment of the invention is shown in the annexed drawings.

Of said drawings:

- 40 Fig. 1 is a side view of a special key bank,
Fig. 2 is a front view of a rack controlled by the differential device of said special key bank,
Fig. 3 is a side view of the shifting means for the actuating cam disk of the printing hammer,
45 Fig. 4 is a front view of the printing hammer and its actuator,

Fig. 5 is a side view of the total lever and means connected therewith.

A machine of this type as referred to, is preferably provided with several banks of special keys. Of said banks the first serves to classify and subdivide the deposits, the second the withdrawals, and the third for balancing actions. In the first mentioned two banks one key is provided for supplementary transactions. For each

special key bank a differential device is arranged which is well known in the art and is also shown and described in the beforementioned Shipley Patent No. 1,628,336. It consists of a driving segment 1 (Fig. 1) which is given first a counter-clockwise and then a clockwise movement in every operation. This segment is actuated by a pair of cams 2 fast on the main drive shaft 25. The cams transmit their movement to the segment by means of a Y-shaped member 4 and a link 5, as it is well known in the art. Normally latched to the segment 1 is a differentially movable member 11, which is moved by the segment 1 on its clockwise movement. The differential member 11 is arrested and unlatched from the driving segment 1 when the latch engages a depressed key.

Pivoted to the differential member 11 is a beam 13 the bifurcated end of which cooperates with a roller 14 on a link 15 for moving the link and roller differentially. At its lower end the link 15 is connected by an arm 17 to a spiral segment 18 loose on a rod 16. The segment 18 meshes with a spiral pinion 19 secured to a shaft 20 which carries a toothed segment 21 (see also Fig. 2). The segment 21 meshes with a rack 23 guided by and on two fixed rollers 22. A projection 24 is provided on the extreme left end of each of the two racks 23 allotted to the special keys for deposit and withdrawal transactions. The projections 24 cooperate (see also Fig. 3) with a lever 26 loosely mounted on a shaft 25. The rack 23 allotted to the third special key bank has no projection 24 because the old balances are printed merely upon the audit strip but not upon the inserted record materials.

The lever 26 is provided with a bent-over portion 27 which lies over an arm 28. The arm 28 is pivoted at 29 (Fig. 3) to a pitman 30 which is guided by a stud 31 and by its bifurcated end on the main shaft 32. A projection of the arm 28 is connected by means of a spring 33 to the pitman 30. The spring 33 tends to rotate the arm 28 counter-clockwise (Fig. 3) and the lever 26 clockwise (Fig. 2). A roller 34 on the pitman 30 projects into the cam groove 35 of a gear 36. As the gear 36 makes a full revolution at each machine operation, the pitman 30 is shifted to the left once at each machine operation, and returned thereafter into the position shown in Fig. 3. The arm 28 partakes in this movement.

A pin 37 provided on a shiftable shaft 38 having secured thereto a bifurcated arm 39 (Fig. 4), extends into the path of the arm 28. The arm 39 engages an annular groove in the hub of a cam disk 41 shiftable, but not rotatably arranged

upon the printer shaft 40, which disk has thereon a narrow cam 57 and a broader cam 58. The cam disk 41 cooperates with the roller 42 of a bell crank lever 43 fast to a shaft 44, by which lever the drive of the printing hammers 45 is effected. The printing hammers 45, the platens 46 of which cooperate with the type wheels 470, are rockably mounted upon a shaft 46. Beside each printing hammer 45 a bell crank lever 47 is arranged, the arm 48 of which engages, under the action of the spring 49 attached to its other arm 50, a pin 51 of the appertaining printing hammer 45. A projection 510 of the lever 47 bears under the action of the spring 49 upon a bail 52, the one arm of which carries a pin 54 on a projection 53. The pin 54 engages a curved slot 55 of a member 56, the left end of which is linked to an arm of the bell crank lever 43.

When the cam disk 41 is positioned as outlined in Fig. 3, the narrow cam 57 is out of the path of the roller 42, which then will be actuated by the cam 58 only. During the counter-clockwise rotation of the shaft 49 in a machine operation, the cam 58 (Fig. 4), by means of the lever 43, rocks the member 56 to the left and by the pin 54 rocks the bail 52. Rocking the bail 52 tensions the spring 49 by means of the lever 47. Thereupon the arm 48 of the lever 47 frees the pin 51, and the printing hammer 45 is lowered clockwise under the action of its own weight. When the cam 58 has left the roller 42, the spring 49 becomes effective and rocks, suddenly, the lever 47 counter-clockwise the arm 48 of which raises, by means of the pin 51, the printing hammer 55, and its platen 46 presses the inserted record material against the type wheels 470 arranged above an ink ribbon.

Normally, during a machine operation the shaft 38 is shifted to the right and the cam 57 is moved into the plane of the roller 42, so that a second hammer stroke is effected thereby. The shaft 38 is shifted to the right in the following manner:—

At the start of a machine operation, the pitman 30 is moved to the left by the curved groove 35. Thereupon the plane surface 59 of the arm 28 slides along beneath the pin 37, till its recess 60 is below the pin 37. When the racks 23 are moved into a position wherein no projection 24 is beneath the free end of lever 26, the bent-over portion 27 of the lever 26 takes an ineffective position, and the arm 28 can rock counterclockwise under the action of the spring 33 till its recess 60 engages with the pin 37, and at the same time its pin 61 disengages a locking pawl 62 pivoted to the frame. In this manner the shaft 38 is coupled with the pitman 30. In the course of the counter-clockwise movement of the gear 36 the pitman 30 is moved again to the right by the cam groove 35. Thereupon the shaft 38 is shifted and the cam 57 is moved into the path of the roller 42. The parts remain in this position, till the pitman 30 is shifted to the left at the beginning of the next machine operation.

When, however, the differential device of the special key bank for deposit and withdrawal is set by the supplemental operation key, the appertaining rack 23 has moved the projection 24 below the lever 26 and rocked the latter counter-clockwise (Fig. 2). The bent-over portion 27 of the bail 26 engages a projection 64 of the arm 28 and moves it against the action of the spring 33 into ineffective position. The lever 26 is freed of the projection 24 only, after,

at the beginning of a machine operation, the cam groove 35 has moved the pitman 30 and the shaft 38 into the left-hand position (Fig. 3). Simultaneously with the disengaging of the lever 28, the locking pawl 62 resumes its normal position under the action of its spring 65 and arrests the shaft 38 in a position, in which the cam disk 57 is out of the plane of the roller 42. When now the pitman 30 is again moved to the right, the lever 28 is held by means of the bent-over portion in ineffective position, so that the straight surface 59 of the lever 28 arrives again below the pin 37, and the shaft 38 remains in the position, in which it is arrested by means of the locking pawl 62. During this machine operation the printing hammer 45 takes only one impression.

The end 66 of a slide 67 guided by its vertical slot on a rigid pin 70 and linked at its upper end to an arm 72 rotatable upon a shaft 71, bears from above under the action of a spring 68 against the bent-over portion 27 of the lever 26. The arm 72 is connected to an indicating device 73, the data of which, visible through a window 74 of the machine cabinet 75, indicate to the machine operator whether the printing hammer 45 performs one or two printing strokes.

The slide 67 carries a pin 76, which cooperates with a locking member 78 rockably arranged on a shaft 77. The locking member 78 has a pin 80 thereon to which a spring 79 is connected and urges the pin 80 against a bell crank lever 81 secured to the shaft 77, which lever normally arrests the locking member 78 in its ineffective position. Secured to the shaft 77 is also an arm 82 (Fig. 5) the roller 83 of which engages a curved slot 84 of an arm 86 pivoted at 85. The arm 86 is connected by means of a spring 87 and a pin 88 to a member 89, the roller 90 of which is guided in the cam slot 91 of the total lever 92. When the total lever 92 is moved out of the adding position, the member 89 and the arm 86 are rocked counter-clockwise by the cam slot 91, and the arm 82 and the shaft 77 clockwise by the curved slot 84 (Fig. 5, compare also Fig. 3). Thereby the locking member 78 is moved above the pin 76 and arrests the slide 67 in the position shown in Fig. 3. Also the arm 28 is held disengaged by the bent-over portion 27 of the lever 26, although the nose 24 is moved out of the path of the lever 26 during the machine operation.

From the arrangement disclosed, it results that the single print is maintained for a total taking operation subsequent to the entering of an amount, at which a printing mechanism has been controlled for single print. When at the end of a total taking operation, during which the projections 24 were moved out of the path of the lever 26, the total lever 92 is restored to adding position, the locking member 78 frees the pin 76, so that the slide 67, under the action of the spring 68, is returned into its inoperative position.

If, during entering operations, no projection 24 is positioned beneath the lever 26, the arm 28 rises and carries slide 67 into its upper position, and, during the machine operation, the arm 28 shifts the shaft 38 into its two-print position, where these parts remain at the end of the machine operation, as before explained. When the total lever is moved to total taking position immediately following such an operation, the locking member 78 is moved beneath the pin 76 and therefore locks the slide in its

upper position, and then the arm 28 is under the control of the racks 23. Then, when no projection is beneath the lever 26 during total taking operations, the arm 28 can shift the shaft 5 38 into the two-print position.

From the above it is clear that the locking member 78 maintains the slide 67 in the position in which it was set during the entering operation that directly precedes a total taking operation, so that the same number of impressions will be made during the subsequent total taking operation.

While the form of mechanism herein shown and described, is admirably adapted to fulfill the objects primarily stated, it is to be understood that it is not intended to confine the invention to the embodiments herein disclosed, for it is susceptible of embodiment in various other forms all coming within the scope of the claims which 20 follow.

What is claimed as new is:

1. In a machine of the class described capable of performing add and total taking operations, and having a printing hammer; a shiftable cam 25 to actuate the hammer a plurality of times for each operation of the machine when in one position and a single time during each operation when in another position; means to shift the cam from one of said positions to another of said 30 positions; manipulative control devices; a differentially settable means set under control of the manipulative control devices; and an element coacting with the differentially settable means and the shifting means to determine into what 35 position the cam is to be shifted by the shifting means; and a total control lever, the combination of a device settable into one of a plurality of positions by the element during adding operations, said device acting to control the element 40 during total taking operations; and a locking element coacting with the device to lock the device in either one of the plurality of positions in which it is set under control of the differentially settable means during adding operations, said 45 locking element movable into locking position by the total lever when the total lever is moved into total taking position to enable the device to control the element whereby the same number of impressions are made during total taking operations as are made during adding operations. 50

2. In a machine of the class described having printing mechanism for printing on record material, including a hammer and an operating means therefor shiftable into two positions, said 55 operating means being effective to actuate said hammer twice when in one of said two positions and once when in the other of said two positions, to make one or two printing impressions during both adding and total-taking operations, a plurality of control keys including a special key, means to shift the operating means from one to the other of said positions, and control means set by the control keys to control the shifting means to shift the operating means into the one- 60 print position upon operation of the special key and into the two-print positions upon operation of any one of the other control keys, the combination of a device settable into either of two positions by the control means during adding operations, the position into which the device is set depending on the position of adjustment of the control means; and connections actuated by the total-taking control means when moved to 65 adjust the machine for total-taking operations, including an element movable to maintain the

device in either position into which it was set by the control means during an adding operation, to thereby control the control means to cause one impression to be made during a total-taking operation following a one-print adding operation, and to allow a two-print operating during a total-taking operation following a two-print adding operation. 5

3. In a machine of the class described, having a printing mechanism for printing on record material, a special key bank for classifying the amounts entered, a total lever, a hammer in said printing mechanism, means operable to cause the hammer to effect two impressions during adding and total-taking operations, and a hammer operation control mechanism controlled by the keys of the special key bank whereby when one of the keys is depressed in adding operations the hammer will be operable to effect a single impression stroke and when another key is depressed the hammer will be operable to effect two printing strokes, the combination of a device set by the hammer operation control mechanism during adding operations; and means adjusted by the total lever for maintaining the device in said set position to thereby control the hammer operation control mechanism to cause one impression to be made during a total-taking operation following an adding operation during which one impression was made, and to allow two impressions to be made during a total-taking operation following an adding operation during which two impressions were made. 20 25 30

4. In a machine of the class described having a printing mechanism operable to print on record material, a special key bank for classifying the amounts entered, a total lever settable to total-taking positions, a printing hammer in said printing mechanism normally operable to effect a plurality of impressions during adding and total-taking operations, a hammer control mechanism including a control plate settable under control of the special keys of said special key bank, and a feeler coacting with the control plate to control the hammer to make one impression stroke 40 when one of said keys is depressed in adding operations, the combination of a device settable by the feeler into different positions determined by the feeler; and locking means controlled by the total lever when it is set to total-taking position, for maintaining the device in the position to which it was set by the feeler during the adding operation to maintain the control mechanism operative during total-taking operations subsequent to an adding operation in which said one of the special keys was depressed, to cause the hammer to make only one impression during the subsequent total-taking operation, or for maintaining the device in the position to which it was set by the feeler during the adding operation to release the control mechanism to the action of the feeler during total-taking operations subsequent to an adding operation in which one of the other of said special keys was depressed to cause the hammer to make one or two impressions during the subsequent total-taking operation. 50 55 60 65

5. In a machine of the class described capable of adding operations and total-taking operations, having printing mechanism, including a printer hammer and a shiftable cam adapted when in one position to operate the hammer for two impressions and when shifted into another position to operate the hammer for one impression, means to shift the cam into either one of the two posi- 70 75

- tions during adding operations and during total-taking operations, a plurality of manipulative devices, means adjusted under control of the manipulative devices to control the shifting means to shift the cam into either the one-impression position or into the two-impression position, said cam adapted to remain in its shifted position at the end of the operation, and a total-taking control manipulative means, the combination of a device settable by the means adjustable under control of the manipulative devices; and locking means set by the total-taking control manipulative means when manipulated into its total-taking position to lock the device in the position to which it was adjusted during the adding operation whereupon the device controls the shifting means to cause the same number of impressions to be made during the total-taking operation immediately following an add operation as were made during the said add operation.
6. In a machine of the class described capable of adding operations and total-taking operations, having printing mechanism, including a printer hammer and a shiftable cam adapted when in one position to operate the hammer for two impressions and when shifted into another position to operate the hammer for one impression, means to shift the cam into either one of the two positions during adding operations and during total-taking operations, a plurality of manipulative devices, means differentially adjustable under control of the manipulative devices, a feeler coacting with said differentially adjustable means adapted to assume either of two positions, said feeler when in one position adapted to disable the shifting means for shifting the cam from the one-impression position into the two-impression position, and total-taking control means, the

combination of a device settable by the said feeler; and means set by the total-taking control means when moved into total-taking position to maintain the device in the position in which it was set by the feeler during the adding operation whereby the device controls the shifting means to cause one impression to be made during total-taking operations immediately following an add operation in which one impression is made and two impressions to be made during total-taking operations immediately following an add operation in which two impressions are made.

7. In a machine of the class described having mechanism for printing on record material, a bank of keys in said machine, total-taking control mechanism, said printing mechanism including a printing hammer and means which is normally operable to operate the hammer to effect a plurality of impressions during a machine operation, a hammer operation control mechanism operable under control of a special key in said bank of keys to control the hammer operating means to prevent a second hammer stroke in an operation when the key is depressed, said control mechanism including a notched plate and a feeler coacting with the notched plate, the combination of means settable by the feeler during each adding operation; and means controlled by the total-taking control mechanism to maintain the last-named means in the position to which it was adjusted during an operation of the machine, to control the hammer operating control mechanism to cause the same number of impressions to be made during a total-taking operation as were made during the adding operation immediately preceding the total-taking operation.

KARL BULLERJAHN.
